UNITED STATES PATENT OFFICE

2,618,379

CIGARETTE DISPENSING CONTAINER

Orval T. Hardy, Shelbyville, Ill.

Application January 13, 1950, Serial No. 138,364

1 Claim. (Cl. 206—41.2)

1

My present invention relates to a container and dispenser arrangement and more particularly to a pocket cigarette container and dispenser.

An object of the present invention is to provide a pocket conforming crush-proof and moisture-proof container for cigarettes and the like.

Another object is to provide a dispensing means in a cigarette container for ejecting or dispensing one cigarette at a time.

The above and other objects and advantages of the present invention will appear more fully hereinafter from a consideration of the detailed description which follows, taken together with the accompanying drawings wherein one embodiment of the invention is illustrated. It is to be expressly understood, however, that the drawings are for the purpose of illustration only and are not designed as a definition of the limits of the invention. Reference for this latter purpose should be had to the appended claim.

In the drawings, wherein like reference characters refer to like parts throughout the several views,

Figure 1 is a side elevation view of my invention.

Figure 2 is a rear elevation thereof.

Figure 3 is a top plan view thereof.

Figure 4 is a bottom plan view thereof.

Figure 5 is a front elevation, a portion near the top of the view being in section to show the bead adjacent the upper edge of the body portion, and the groove for said bead, the groove being adjacent the lower edge of the slidable cover for the device.

Figure 6 is a sectional view in which dotted lines indicate the outward or forward limit of the cover when it is slid forward to permit loading the device with cigarettes, while the somewhat heavier dotted lines above the cover show the lifted position of the cigarette as it is dispensed by the dispenser member which is activated by moving upwardly the little button protruding from the front of the body portion of the invention.

Figure 7 is a sectional view taken on the line 7—7 of Figure 6, showing the full pack of cigarettes contained within the body of the device, with one cigarette shown in position to be lifted from the same, by means of the dispenser member above mentioned.

Figure 8 is a perspective view of the dispenser member as seen from the rear, or from the inside face as assembled.

Figure 9 is a fragmentary top plan view showing the cover as moved forward to permit the loading of the device with cigarettes.

2

Referring to the drawings and first with particular reference to Figures 5 and 6, my invention includes an oblong container 10 open at the top having flat sides 11 and 12, rounded ends 13 and 14 and a bottom portion 15 formed with a relatively small countersunk depression 16 having an opening 17.

One rounded end 14 of the container is preferably made to converge into a nose or rounded apex 18 and is cut through to form an elongated slot 19, see Fig. 5, intermediate and perpendicular to the bottom and top edge of the container. Mounted for sliding movement in the slot is a headed rivet 20. The headless end of the rivet is secured to the leg of an L-shaped ejector bar 21 curved transversely to conform to the round nose 18 of end 14 and so that the foot 22 of the ejector bar will seat within the countersunk depression 16 over the opening 17 when the headed rivet is at the lower end of the slot 19, as in Fig. 6.

The L-shaped ejector or dispenser 21 when the foot 22 is seated in the depression 16 extends about three-fourths of the height of the container 10 and when the rivet is slid upward in the slot 19 will just slightly project above the container rim as shown in dotted lines in Figure 6. This is sufficient to selectively eject or dispense a cigarette from the container 10 through a spring bias trap lid 24, see Figs. 1, 3 and 6.

30 The trap lid 24 swings outward on a hinge 25 against the action of a spring 26 around the hinge. The hinge connects the trap lid 24 to a slidably mounted main container cover 27.

The cover 27 is formed on each side with elongated grooves 28 and 29, each of which snugly fit over elongated lugs 30. These lugs 30 are substantially one-half the length of the grooves and serve as stops for the cover when it is moved forward to open position as shown in Figures 6 and 9, or when moved to closed position as in Fig. 1.

When the cover is in forward open position the container 10 may be filled with cigarettes from a standard size package. After filling the container the cover is closed and the cigarettes may now be singly ejected or dispensed by pushing upward on the headed rivet 20. This is because the cigarettes are movable into the nose 18 of the end 14 so that one cigarette will always rest on the foot 22 of the transversely curved ejector bar.

When the ejector hoists a cigarette to dispensing position, the foot 22 uncovers opening 17 in depression 16 and any loose tobacco will readily drop out of the opening and eliminate the chance of interference with the snug seating or nesting

of the foot 22 in the countersunk depression 16.

The head of the rivet 20 may be capped with a button and the shank under the head formed into a reduced neck portion for more efficient action in the slot 19, if desired. And the spring of the trap lid 24 is very light so as to offer only slight resistance to the end of a cigarette being dispensed.

Without further description, it is believed that my invention is clearly understandable to others and while only one embodiment has been described, it is to be expressly understood that various arrangements and combinations of the parts, which may now occur to others skilled in this art are likewise to be considered a part hereof. To determine the scope of my invention, reference should be had to the appended claim.

What I claim is:

A cigarette dispensing container having flat side walls and a bottom portion having a depression therein and an opening smaller than the depression, one curved end wall and one end wall which converges into a rounded nose serving to position a single cigarette into dispensing position, said container being open at the top, an elongated slot formed in the rounded nose end wall of the container extending intermediate the bottom and top thereof, a headed rivet with a reduced neck slidable between the walls of said slot, the shank end of the rivet being secured to an ejector member, said ejector member having a transverse curved leg conforming to the interior of said rounded nose at one side and to the circumference of a cigarette on the other side, and a foot portion at substantially right angles to the 35

leg for supporting a cigarette to be dispensed, said foot portion of the ejector means being contained in the depression of the bottom of the container and covering the opening in the bottom thereof, a slidible top for the container having a spring urged auxiliary lid carried in the top thereof to be pushed open by a cigarette raised on the ejector when the headed rivet is moved to the upper end of said slot, with means for retaining the cover on the container, said means comprising elongated lugs on each side wall of the container co-acting with grooves formed in the side walls of the cover of the container, the grooves in the side walls of the top of the container being substantially twice the length of the lugs formed on the walls of the container.
